UNITED STATES PATENT OFFICE.

JOHN FRIDGEN, OF KANSAS CITY, MISSOURI, ASSIGNOR, BY DIRECT AND MESNE ASSIGNMENTS, TO CHARLES B. ROYAL, OF RIVER FOREST, ILLINOIS.

APPARATUS FOR LUBRICATING ENGINE-TRUCKS AND DRIVING-JOURNALS.

No. 806,130.

Specification of Letters Patent.

Patented Dec. 5, 1905.

Application filed January 3, 1905. Serial No. 239,342.

To all whom it may concern:

Be it known that I, JOHN FRIDGEN, a citizen of the United States, residing at Kansas City, in the county of Jackson and State of Missouri, 5 have invented certain new and useful Improvements in Apparatus for Lubricating Engine-Trucks and Driving-Journals; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 My present invention relates to an apparatus for lubricating engine-trucks and driving-journals, and more particularly to a lubricating apparatus for the driving-journals of a locomotive, in which grease or hard oil contained in a suitable cellar is applied to the journals under a forced feed.

20 It is the object of my invention to provide a device of the class described which is simple and economical in construction and operation 25 and comprises certain features of novelty and utility which will be fully described and pointed out in the claims, reference being had to the accompanying drawings, forming part of this specification, in which like reference- 30 numerals refer to like parts throughout the several views, and in which—

Figure 1 is a perspective view of a driving wheel, journal, and driving-box equipped with my improved lubricator. Fig. 2 is a sectional view of the cellar, showing the different apartments and connections. Fig. 3 is a vertical sectional view on the line $\alpha\alpha$, Fig. 2, looking in the direction of the arrow. Fig. 4 is a detail view of the bottom plate, which retains the cellar in 35 the driving-box. Fig. 5 is a detail view of one of the set-screws and coil-springs on the bottom plate. Fig. 6 is a slight modification of Fig. 1, showing the force-feed operating from the bottom of the cellar-block. Fig. 7 40 is a vertical sectional view of the feed-cylinder and cellar of Fig. 6. Fig. 8 is a transverse sectional view on the line $y\gamma$, Fig. 7. Fig. 9 is a detail view of a portion of the bottom plate used with the bottom-feed modification. Fig. 10 is a detail view of a portion 50 of the cellar, showing the bushing and feed-port.

Referring more to details of the parts, 1 is

the driving-wheel of a locomotive, which is mounted on the driving-axle 2.

3 is the driving-box carrying the engine, and 4 is the driving-box brass forming the top journal-bearing, which may be secured in any suitable manner in the driving-box. Fitting within the lower portion of the driving-box 60 is the lubricant-cellular block 5, the upper face of which is provided with a semicircular groove lined with a suitable bushing 6, preferably Babbitt metal, for forming the lower half for the axle-bearing. At the bottom of 65 bushing 6 is a groove 11, forming a bed into which the lubricant from the cellar is fed, as will presently be described, to contact with the axle. Extending through one-half of cellar-block 5 is a cylindrical recess 7, in the inner end of which is a passage-way 8, leading into a second smaller cylinder 9, said cylinder 9 in turn opening into the lubricant-cellar 10, which occupies about one-half of the block 5. Extending longitudinally for nearly the 70 length of the block and connecting the cellar and the contact-bed 11 of the bearing is the port 12.

The inner surface of cylinder 7 is threaded for a short distance from its outer end to receive the threaded cap 13, which closes the mouth of the cylinder. Projecting through a perforation in the center of and having a threaded connection with cap 13 is a plug 14, provided with the spring-pocket 15. Projecting through pocket 15 and through a perforation in the head 16 of said plug is the rod 17 of a piston 18, said piston fitting snugly within cylinder 7. Surrounding rod 17 is an expansion-spring 19, which fits partly within 80 pocket 15, with its outer end seated against the cap 13 and its inner end bearing against piston 18. The outer surface of plug 14 is threaded throughout its length and is provided with a jam-nut 20 for retaining cap 13 in its 85 position in the cylinder.

21 is a bottom plate adapted to be secured by means of studs, which pass through the corner-flanges 22, to the bottom of the driving-box, said plate when in place retaining the 90 cellar-block in its position in the driving-box.

Fitting in spring-pockets 23 are short stiff compression-springs 24, which bear against the bottom of the cellar-block and yieldingly retain same in position, with the bottom bushing 105 always in contact with the axle. Spring-

pockets 23 are preferable in the upper ends of a pair of set-screws 25, which project through plate 21. When so constructed, the upward pressure against the block may be regulated 5 as desired by the turning of said screws.

26 is a set-screw projecting upwardly from the inner end of the plate to act as a keeper for retaining the block in the box.

In the operation of my device the driving-10 box is placed on the journal, with the driving-brass, which has been previously secured in the box, resting on the journal. The cellar-block carrying the lower bushing is then adjusted in the box and secured in place by 15 means of the bottom plate 21, as described, the set-screw in the end of the plate preventing the escape of the block from the box. When the block has been properly adjusted and secured in the driving-box, the cylinder-20 cap, with the piston, is removed and the cellar filled with grease or hard oil by feeding same into the first cylinder and forcing it therethrough into the smaller cylinder and thence into the cellar proper. When the cellar and cylinder have been filled, the piston 25 is placed in the outer cylinder, the cylinder-cap secured in place, and the threaded plug 14 threaded into said cap with the spring in its pocket, with the plug and the piston-rod 30 projecting through the head 16. The jam-nut on the plug is tightened for the purpose specified. As the cylinder is full of grease or hard oil it will be possible for the piston to project only a short distance thereinto. Conse-35 quently the plug projects almost its entire length without the cylinder, with the piston-rod projecting through the cap of the plug. As the axle turns the grease or hard-oil lubricant is fed through the port into the contact-40 bed of the bushing to contact with the axle, and as the supply in the contact-bed is exhausted a fresh supply is forced upwardly thereinto from the cellar by the piston being forced forward against the lubricant in the 45 main cylinder by the compression-spring 19. As the compression-spring forces the piston inwardly the rod follows until only a small portion of it projects beyond the head 16, when plug 14 should be screwed farther into 50 the cylinder, it being possible to instantly determine the supply of lubricant in the cellar at any time by the distance the plug and rod project beyond the cylinder. In this way the inspector can instantly tell when the cellar 55 needs filling, and the liability of a dry cellar and resultant hot box is reduced to a minimum. By having the pin seated in the pocket in the threaded plug the tension of the spring may be quickly and easily regulated.

60 By referring to Fig. 3 the advantage of a lubricator in case of a hot-box is apparent. It will be noticed that the cellar-block on the side opposite the cylinder is but a shell, the lubricant-cellar extending upwardly and con-65 forming to the curve of the axle-bushing. In

case the journal should become heated the heat is quickly conducted through the bushing to the lubricant, which becoming heated expands and forces a quicker feed of grease or oil through the port to the contact-bed, 70 the oil also tending to cool the bearing. As the cellar extends upwardly to a higher point than the contact-bed, the lubricant would tend to flow if melted into said bed. There could, however, be no waste of the lubricant in case 75 of the hot-box melting the lubricant, as the only means of its escape is through the port into the contact-bed of the axle. Should it be necessary to replace one of the bushings, 80 it is a simple matter to remove the cellar-block, renew the bushing, and replace the block in the box. In recharging the cellar it is only necessary to remove the cylinder-cap and piston and repeat the filling operation, 85 which has been described.

In Fig. 6 I show a driving-axle carrying an eccentric. With such a construction I employ the slight modification of my cellar-block, as shown in Figs. 6, 7, 8, 9, 10. With the eccentric on the axle, as shown, the plug and 90 rod projecting from the side would interfere with its action, so I provide a cellar-block substantially similar to the one described, with the exception that at one end of the main cylinder I provide a drop-cylinder, with which 95 the piston and its parts are connected and which they operate in the same manner as formerly described, with the exception that their action is vertical instead of horizontal. With this block I provide a circular opening 100 27 near the center of the horizontal cylinder, through which the lubricant is fed into the cellar. The bottom plate 21^a is substantially 105 similar to the bottom plate 21, the exception being the lip 28, which fits within the socket 29 in the block and replaces the set-screw 26 and the addition to plate 21^a of a pocket 30, 110 adapted to fit over the depending cylinder.

A lubricator constructed according to my invention will when properly handled run for 110 sixty thousand miles and when emptied can be easily refilled without removing the cellar-block from the driving-box. As the feed-port is usually made one inch wide, it is impossible to clog same, and a sufficient quantity of lubricant is always in the contact-bed to lubricate both the axle and the hub of the wheel. The cellars are dust-proof, and a suitable bushing is provided for the axle throughout the length of the block, so that in case of 115 a broken tire the wheel may be carried by the block up off the rail and be lubricated, so as to run cool, while it is ordinarily necessary with other lubricating means when such an accident occurs for the cellar-block to be removed and a wooden block inserted to carry the journal.

While I have specifically described the various parts of my device, I do not wish to be understood as limiting myself to the exact de- 120 125 130

tails of structure therein described and shown, inasmuch as the same may be varied without departing from the spirit of my invention.

Having thus described my invention, what I claim as new therein, and desire to secure by Letters Patent, is—

1. In a device of the class described, in combination with a suitable driving-box, a lubricant-cellular block mounted in said box comprising a suitable cellar having a feed-opening to the axle, a compression-cylinder adjacent to said cellar and a smaller cylinder connected with said compression-cylinder and opening into said cellar, a piston in said compression-cylinder, and means for maintaining a yielding inward pressure on said piston.
2. In a device of the class described, in combination with a suitable driving-box, a lubricant-cellular block mounted in said box, comprising a suitable cellar having a feed-opening to the axle and a compression-cylinder adjacent to and connected with said cellar, a piston in said cellar having a rod projecting through the head of said cylinder, and a coil-spring surrounding said rod, and maintaining an inward pressure on said piston for the purpose set forth.
3. In a device of the class described, in combination with a suitable driving-box, a lubricant-cellular block mounted in said box, comprising a suitable cellar having a feed-opening to the axle and a compression-cylinder adjacent to and connected with said cellar, a suit-

able head in said cylinder, a hollow plug, having a central spring-pocket threaded into said head, a piston in said cylinder, a rod on said piston projecting through said spring-pocket and through a perforation in the head of said plug, and a coil-spring surrounding said rod with one end within and seated against the base of said pocket, and its other end bearing against said piston substantially as and for the purpose set forth.

4. In a device of the class described, the combination with an open-bottom driving-box, of a plate secured to the bottom of said box, means on said plate for yieldingly supporting a cellar-block within the box, and a suitable cellar-block supported by said means.

5. In a device of the class described, the combination with a journal-box and a cellar-block carried therein, of a bottom plate, having threaded perforations therein, adapted to be secured to the bottom of said journal-box, threaded studs, having nests in their upper ends, projecting through said perforations, and coil-springs seated in said nests and supporting said cellar-block substantially as set forth.

In testimony whereof I affix my signature in presence of two witnesses.

JOHN FRIDGEN.
